UNITED STATES PATENT OFFICE.

RUBEN F. BARKER, OF MARINETTE, WISCONSIN, ASSIGNOR OF ONE-HALF
TO MICHAEL CORRY, OF MARINETTE, WISCONSIN.

SAWMILL SET-WORKS.

SPECIFICATION forming part of Letters Patent No. 737,563, dated September 1, 1903.

Application filed June 23, 1903. Serial No. 162,703. (No model.)

To all whom it may concern:

Be it known that I, RUBEN F. BARKER, a citizen of the United States of America, and a resident of Marinette, county of Marinette, 5 and State of Wisconsin, have invented certain new and useful Improvements in Sawmill Set-Works, of which the following is a specification, and which are illustrated in the accompanying drawings, forming a part thereof.

10 The invention relates to that type of sawmill set-works in which there is employed a motor having a piston reciprocating between positive stops and which motor is retarded by means of a check-cylinder containing a fluid, 15 such as oil, which is passed around a piston reciprocating in the cylinder through a by-pass at each stroke of the motor-piston.

10 The object of the invention is to provide for the variable control of the by-pass, so that 20 it shall be closed or partially closed toward the end of the stroke, thus increasing the retardation of the motor, while interposing less resistance during the middle of the stroke.

This object is attained by the use of a valve 25 in the by-pass of the retarding or check cylinder, which valve is opened and closed by the action of the motor, and provision is made for relatively varying the action of the valve as the length of the stroke of the motor is 30 varied.

The invention is illustrated in the accompanying drawings, in which—

Figure 1 is a plan view of the motor mechanism of a sawmill set-works. Fig. 2 is a side 35 elevation of the same, some of the parts being in section. Fig. 3 is a detail side elevation of the motor mechanism, showing one form of the invention. Fig. 4 is a detail of the retarding-cylinder. Fig. 5 is a plan view 40 of a sawmill-carriage, and Fig. 6 is a detail of one of the connections.

There is shown in the drawings at 10 the cylinder of a reciprocating engine; at 11, a retarding-cylinder arranged tandem with the 45 power-cylinder; at 12, the piston-rod, which is common to both cylinders; at 13, the cross-head of the motor provided with rack-gears; at 14, a segmental gear intermeshing with the rack of the cross-head and mounted upon a 50 rocker-shaft 15; at 16, the usual set-shaft of a sawmill-carriage; at 17, the pawl-carriers

for coöperating with the ratchet-wheel ordinarily carried by such a set-shaft; at 18, the link connecting one of the pawl-carriers with the rocker-shaft 15, and at 19 the knees of 55 the sawmill-carriage with which the set-shaft 16 is in geared connection, as usual.

The retarding-cylinder 11 is provided with a by-pass (shown in Fig. 4) connecting its two ends, and in this by-pass there is located 60 a two-way rocker-valve 20, controlled by means of a crank-arm 21, which in the preferred form of construction illustrated in Fig. 3 is actuated from the cross-head 13 through the medium of a rock-lever 22, pivoted to the cross-head at 23 and connected with the crank-arm 21 by means of a link 24, the rock-lever 22 being pivoted at 25 to a link-bar 26, which is pivoted at 27 to a fixed part, as the cylinder 11, and is pivotally connected with the usual stop-lever 28 by means of a block 29, which is in sliding engagement with the link-bar 26 through the medium of a loop 30.

The rock-lever 22 is curved to an arc, of 75 which the link-bar 26 is a radius, and is slotted, so as to slide upon the pivot-pin 23. The link 24 is in pivotal engagement with the rock-lever 22 through the medium of a yoke 31, adapted to be fixed to the rock-lever and 80 provided with the pivot 32 for the engagement of the link.

The stop-lever 28 is of the well-known form and projects across the path of the cross-head 13 and may be adjusted so as to vary 85 the stroke of the motor-piston. As it is swung about its pivot it raises and lowers the link-bar 26, and with it the rock-lever 22, thereby moving the center about which this rock-lever oscillates relatively as to the pivot-pin 23, by means of which the lever is oscillated, thereby varying the throw of the lever 90 relatively as to the range of movement of the cross-head, and thus maintaining a uniform movement of the valve 20 whatever may be 95 the stroke of the motor. This variation between the stroke of the motor and the throw of the valve 20 may be worked out in various ways—as, for example, by means of the construction illustrated in detail in Fig. 2 and 100 disclosed also in Fig. 1.

In this form of construction the connection

between the cross-head 13 and the link 24, by means of which the valve is actuated, is through the medium of a rock-lever 33, swinging about a pivot 34, fixed in the frame of 5 the motor, the rock-lever 33 being connected with the cross-head by a link 35. The link 24 is pivoted to a block 36, which is in sliding engagement with the rock-lever 33, and this block is moved vertically by the action of the 10 stop-lever 28 through the medium of an arm 37, swinging through a fixed pivot set in the frame of the machine, and connected with the link 24 by means of a link 38 and with the lever 28 by means of a link 39. As the lever 15 28 is swung about its pivot it raises or lowers the arm 37, and with it the link 24 and block 36, thus varying the throw of the crank-arm 21 relatively as to the range of movement of the cross-head and providing for maintaining 20 a uniform action of the valve, though the stroke of the motor be varied. In this instance also the rock-lever 33 is curved to an arc and its radius is the link-bar 24, so that the movement of the block 36 longitudinally 25 upon the rock-lever 33 does not effect any movement of the valve. While the centers of oscillation of the rock-lever 33 and the link 38 are not identical, there is so little difference between them and the pivot-pins connecting the link 24 with said block and link 30 move through so nearly similar arcs that no cramping occurs.

I claim as my invention—

1. In a power-actuated set-works for saw-mills, in combination, a motor having a variable stroke; a retarding device comprising a cylinder having a by-pass connecting the ends of its chamber, a valve in the by-pass, and a piston reciprocating in the cylinder and 35 operatively connected with the motor; and adjustable operative connection between the motor and the by-pass valve.

2. In a power-actuated set-works for saw-mills, in combination, a motor having a variable stroke; a retarding device comprising a cylinder having a by-pass connecting the ends of its chamber, a valve in the by-pass, and a piston reciprocating in the cylinder and operatively connected with the motor; 45 adjustable operative connection between the motor and the by-pass valve; and means for adjusting such connection to maintain a uniform throw of the valve though the motor-stroke be varied.

3. In a power-actuated set-works for saw-mills, in combination, a motor having a vari-

able stroke; a retarding device comprising a cylinder having a by-pass connecting the ends of its chamber, a valve in the by-pass, and a piston reciprocating in the cylinder 60 and operatively connected with the motor; adjustable operative connection between the motor and the by-pass valve; and means for varying the motor-stroke and maintaining uniform throw of the by-pass valve. 65

4. In power-actuated set-works for saw-mills, in combination, a motor; a retarding device comprising a cylinder, a piston movable in the cylinder and a by-pass around the piston; a rock-valve controlling the by-pass; operative connection between the motor and the piston of the retarding device; 70 an oscillating arm actuated by the motor; link connection between the arm and valve; and means for relatively shifting the center 75 of oscillation of the arm and the point of attachment thereto of the link connecting said arm.

5. In a power-actuated set-works for saw-mills, in combination, a motor; a retarding 80 device comprising a cylinder, a piston working therein, a by-pass connecting the two ends of the cylinder-chamber, and a valve in the by-pass; operative connection between the motor and the piston of the retarding device; 85 a movable positive stop for the motor; an oscillating arm driven by the motor; connection between the arm and the by-pass valve; and means actuated by the positive 90 stop for relatively changing the center of oscillation of the arm and the point of attachment thereto of the means connecting such arm with the valve.

6. In a power-actuated set-works for saw-mills, in combination, a motor-cylinder and 95 a retarding-cylinder each having a reciprocating piston; connection between such pistons; a by-pass connecting the ends of the retarding-cylinder chamber; a valve in said by-pass; a cross-head driven by the piston 100 of the motor-cylinder; an arm pivotally attached to the cross-head and in sliding engagement with its pivot; a stop-lever; a second arm oscillating upon a fixed pivot and in pivotal engagement with the first-mentioned 105 arm; and a block slidable upon the second arm and pivotally attached to the stop-lever.
